(57) **CLAIM**

The ornamental design for a wall-mounted lighting fixture, as shown.

DESCRIPTION

FIG. 1 is a three-dimensional view, generally from the bottom right front, of a wall-mounted lighting fixture, showing our new design.

FIG. 2 is another three-dimensional view, generally from the top right front, thereof;

FIG. 3 is a front elevational view thereof;

FIG. 4 is a left side elevational view thereof, the right side being a mirror image;

FIG. 5 is a top plan view thereof;

FIG. 6 is a bottom plan view thereof;

FIG. 7 is a rear elevational view thereof;

FIG. 8 is a three-dimensional view, generally from the bottom right front, of a second embodiment of our new design, the top plan view and the rear elevational view of the second embodiment being identical to FIGS. 5 and 7, respectively;

FIG. 9 is another three-dimensional view, generally from the top right front, thereof;

FIG. 10 is a front elevational view thereof;

FIG. 11 is a left side elevational view thereof, the right side being a mirror image; and,

FIG. 12 is a bottom plan view thereof.
